UNITED STATES PATENT OFFICE.

JOSEPH BOYLE BOOMER AND WALTER STROWGER, OF TORONTO, ONTARIO,
CANADA.

MARKING-POT.

SPECIFICATION forming part of Letters Patent No. 365,361, dated June 28, 1887.

Application filed July 29, 1886. Serial No. 209,497. (Model.)

To all whom it may concern:

Be it known that we, JOSEPH BOYLE BOOMER and WALTER STROWGER, subjects of Her Majesty Queen Victoria, and both residents of 5 the city of Toronto, in the county of York, in the Province of Ontario and Dominion of Canada, have invented a new and useful Tank-Feeding Marking-Pot, of which the following is a specification.

10 Our invention relates to improvements in marking-pots in which a tank or reservoir is introduced, from which a supply is drawn by the person using the same as necessity requires, which results in, first, a saving of the paint 15 used; secondly, protects the paint from dust, dirt, and other foreign substances, and also from thickening; thirdly, a saving of the brushes used in connection with the pot; fourthly, a certainty of cleanliness, by reason 20 of the water-tight and air-tight tank or reservoir and the sluice-gate, which is not secured by any other paint-pot now in use. We attain these objects by the design illustrated in the 25 accompanying drawings hereto annexed, illustrating the section, side view, and end view.

Letter E of the section refers to the tank or reservoir, which is air-tight and water-tight, A being the screw-cap covering the inlet to this tank.

30 F is the auxiliary tank, which is separated from E by the sluice-gate D, which is raised when paint is required in the auxiliary tank F from the water and air tight tank E, and then shut down when the supply required is 35 obtained.

G is a well in the auxiliary tank F, into

which the brush is introduced while it is in use. The bottom of this well G is perforated with holes to allow the entering in of the paint from the auxiliary tank F after it has been obtained from the air and water tight tank E. 40

H is the handle of the paint-pot, used to carry it about or hold it while in use; I, a ring attached to the handle H; C, a ring attached to the top of the sluice gate D, by which the 45 sluice-gate is raised or shut down.

B is a spring on the top of the tank for holding the paint-brush when not in use.

We are aware that prior to our invention paint-pots have been made with two tanks. 50 We therefore do not claim the union of two tanks in one paint-pot as our invention; but

What we do claim as our invention, and desire to secure by Letters Patent, is—

1. The union in one paint-pot of a water-tight and air-tight tank or reservoir, E, by means of the sluice-gate D, with an auxiliary tank, F, in which there is a fountain or well, G, as herein shown and described. 55

2. The combination of the inlet to the air and water tight reservoir E, covered by the screw-cap A, and the outlet of this reservoir regulated by the sluice-gate D. 60

3. The sluice-gate D at the union of the two tanks, substantially as shown, for the purpose 65 specified.

JOSEPH BOYLE BOOMER.
WALTER STROWGER.
